CLAIM

The ornamental design for a hair dryer, as described.

DESCRIPTION

FIG. 1 is a front and left side perspective view of a hair dryer showing my new design;

FIG. 2 is a front and right side perspective view thereof;

FIG. 3 is a rear elevational view thereof;

FIG. 4 is a left side elevational view thereof; and,

FIG. 5 is a front elevational view thereof.

The undisclosed bottom portion of the handle element is flat and plain except for the appearance of the cord.
